UNITED STATES PATENT OFFICE.

ALLAN W. CAMPBELL, OF CLIFTON, NEW JERSEY.

CALCULATING-MACHINE.

1,178,297.

Specification of Letters Patent.

Patented Apr. 4, 1916.

Application filed September 14, 1914. Serial No. 861,575.

To all whom it may concern:

Be it known that I, ALLAN W. CAMPBELL, a citizen of the United States, and a resident of Clifton, in the county of Passaic and State of New Jersey, have invented a new and Improved Calculating-Machine, of which the following is a full, clear, and exact description.

The object of the invention is to provide a new and improved calculating machine more especially designed as an aid in making up pay rolls to enable the cashier or other person to accurately and quickly determine the number of bills and coins of different denominations required in paying off the employees.

In order to accomplish the desired result use is made of selective keys, denomination translating means controlled by the said keys, and indicating means controlled by said translating means and indicating the number of bills and coins of different denominations aggregating in amount the total money value of the actuated selective keys.

A practical embodiment of the invention is represented in the accompanying drawings forming a part of this specification, in which similar characters of reference indicate corresponding parts in all the views.

Figure 1 is a plan view of the calculating machine with the parts broken out; Fig. 2 is a sectional side elevation of the same on the line 2—2 of Fig. 1; Fig. 3 is a cross section of the same on the line 3—3 of Fig. 1; and Fig. 4 is a plan view of a key plate for the "one cent" or "one dollar" selective key.

The calculating machine is preferably mounted on a suitably constructed casing A in the top of which are mounted to slide up and down two sets of selective keys B and C, of which the keys B are marked and represent money values and are arranged in columns indicating units and tens of dollars. The keys C are marked and represent money values in cents from 1 to 99 cents, as plainly indicated in Fig. 1. The keys B are adapted to actuate denomination translating devices in the form of racks D, D', D², D³ and D⁴ controlling indicating clevises in the form of counters E, E', E², E³ and E⁴, visible through openings A' in the top of the casing A and indicating the number of bills of different denominations aggregating in amount to the money value of the selective keys B pressed at the time and also indicating the total number of bills of different

denominations required for paying off the employees. The indicating device E indicates \$1.00 bills, the indicating device E' indicates \$2.00 bills, the indicating device E² indicates \$5.00, the indicating device E³ indicates \$10.00 bills and the indicating device E⁴ indicates \$20.00 bills. For larger amounts an extra key F is provided and directly connected with an indicating device 65 or counter E⁵ for indicating the number of \$100.00 bills required in making up the pay roll, the counter being visible through an opening A² in the top of the casing A. The selective keys C are adapted to actuate a 70 series of denomination translating means in the form of racks G, G', G², G³ and G⁴ controlling indicating means in the form of counters H, H', H², H³ and H⁴ visible through openings A³ in the top of the 75 casing A. The counter H indicates the number of pennies, the indicating device H' indicates the number of nickels, the indicating device H² indicates the number of dimes, the indicating device H³ indicates the 80 number of quarters and the indicating device H⁴ indicates the number of half dollars required in paying off the employees. It is understood that each counter has units, 85 tens, hundreds and thousands number wheels to indicate the total amounts of the bills and coins of different denominations required in paying off the employees.

In order to actuate the different racks G, G', G², G³ and G⁴ when a key C is 90 pressed, the following arrangement is made: Each key C is provided within the casing A with a plate I having a series of notches I', I², I³, I⁴ and I⁵ in register with the racks G, G', G², G³ and G⁴, and the said 95 notches are of more or less depth according to the throw to be given to the corresponding rack G, G', G², G³ or G⁴. Each of the racks G is mounted to move up and down on a pair of lazy tongs J pivoted in the 100 bottom of the casing and pressed on by a spring K to normally hold the rack G and the keys B and C in uppermost position. The rack G engages a segmental gear wheel L mounted to oscillate in the casing A and carrying a pawl N in mesh with a ratchet wheel N' secured on a shaft N² on which the segmental gear wheel L is mounted to swing loosely. On the shaft N² is secured a gear wheel O in mesh with an intermediate gear wheel O' in mesh with a gear wheel O² secured 110 on the shaft of the corresponding

counter H, H', H², H³ or H⁴, so as to actuate the same, each counter being provided with the usual number wheels indicating units, tens, hundreds and thousands and driven from the gear wheel O² in the usual manner. As such counters are of the usual construction it is not deemed necessary to describe the same in detail. The racks D, D', D², D³ and D⁴ are mounted similarly to the racks G, G', G², G³, G⁴ and are connected by the same mechanisms with the several counters E, E', E², E³ and E⁴ so that further description of the same is not deemed necessary.

15 It is understood that the notches I', I², I³, I⁴ and I⁵ are so arranged that the corresponding racks G, G', G², G³, G⁴, D, D', D², D³ and D⁴ are actuated according to the amount represented by a key and to be translated in coins or bills of a corresponding value. The notches are of such a depth that a throw given to a rack may be a full stroke for four coins or bills, a half stroke for two coins or bills, or a quarter stroke for one coin or bill. If one or more racks of a bill or coin series are not to be actuated the notch is sufficiently long so that the actuated plate does not come in contact with the corresponding rack. Thus the throw for the coin counter H is either single, double, triple or quadruple so that either one, two, three or four pennies are indicated at a time, while the throw for the counters H', H² and H⁴ is always single, and that for the counter H² is either single or double. The throw for the bill counters E, E² and E³ is always single, that for the counter E' may be single or double, and that for the counters E⁴ may be single, double, triple or quadruple.

40 It is understood that for paying say 91 cents in the least number of coins it requires a half dollar, a quarter, a dime, a nickel and a penny; and for paying \$38.00, for instance, in the least number of bills, it requires one \$20. bill, a \$10. bill, a \$5. bill, a \$2. bill and a \$1. bill. As shown, for instance, in Fig. 3, the plate I for the key C marked "99 cents" has its notches so arranged that when the said key is pressed the rack G is moved a full stroke as the notch I' is practically of little or no depth thus causing turning of the counter H to indicate 4 cents. The notch I² is of full depth and hence the movement of the plate I does not affect the rack G' at all and consequently the nickel counter H' is not actuated. The notch I³ is of half the depth of the notch I² and when the plate I is moved it shifts the rack G² a distance so that the counter H² indicates 2 dimes. The notches I⁴ and I⁵ are of three-fourths the depth of the full notch I² so that the racks G³ and G⁴ are actuated to cause the counters H³ and H⁴ to indicate 1 quarter and 1 half dollar, respectively. It will thus be seen that the total amount of coins required for

making 99 cents is 1 half dollar, 1 quarter dollar, 2 dimes and 4 cents. The plate I for the selective coin key "1" shown in Fig. 4 has a notch I' of the depth of the notches I⁴ and I⁵, Fig. 3 while the remaining notches 70 are of a depth corresponding to the notch I² shown in Fig. 3, so that when the coin selective key C marked "1" is pressed the counter H only is actuated to indicate 1 penny. In case the wage of one of the employees 75 amounts to say \$99.99, the cashier first presses the selective bill keys B marked "9" in the units and tens columns, and in doing so the counters E⁴, E³, E² and E' are actuated to indicate four \$20. bills, one \$10. 80 bill, one \$5. bill and two \$2. bills, and then the cashier presses the selective coin key C marked "99" and thereby causes the counters H⁴, H³, H² and H to be actuated to indicate 1 half dollar, 1 quarter dollar, 2 dimes and 85 4 pennies, as previously explained. For the next wage on the pay roll, say \$45., the cashier presses the key B marked "4" and located in the second column and the key B marked "3" located in the first or unit column, and 90 in doing so the counters E² and E⁴ are actuated and advanced, that is, the counter E² is shifted to add one \$5. bill while the counter E⁴ is shifted to add two \$20. bills to the amounts previously registered, the said \$5. 95 bill and the two \$20. bills aggregating the wage amount of \$45.

95 In using the machine, the cashier presses the keys B and C successively according to the wages as listed for the several employees 100 so that the counters finally indicate the number of bills and coins required for paying off the employees according to the pay roll, the aggregate amount of the said bills and coins corresponding exactly to the total amount of 105 the pay roll.

It is understood that the degree of depression of the racks G, G', G², G³, G⁴ and D, D', D², D³, D⁴ depends on the amount represented by the corresponding key and the 110 number of bills or coins required for making up the said amount.

115 As shown in Fig. 1, the total amount of the pay roll figures up to be \$4,669.21, represented by 5 one hundred dollar bills, 38 twenty dollar bills, 152 ten dollar bills, 168 five dollar bills, 47 two dollar bills, 531 one dollar bills, 320 half dollars, 670 quarter dollars, 854 dimes, 171 nickels and 276 pennies.

120 Having thus described my invention, I claim as new and desire to secure by Letters Patent:

125 1. A calculating machine, comprising selective keys each provided with a plate having one or more vertical notches of different depths opening at the lower edge of the plate, a denomination translating mechanism arranged below the said plate and controlled by the latter, the degree of movement of 130

- said mechanism depending on the depth of the notches, and a counter controlled by the said denomination translating mechanism and indicating the number of pieces of 5 money of different denominations aggregating the money value of the key pressed.
2. A calculating machine for use in making up pay rolls, comprising manually controlled selective keys, denomination translating means comprising racks mounted to move up and down, a plate carried by each of said keys and having a series of spaced notches opening at the lower edge of the plate and in register with the respective 10 racks, the notches of each plate being of more or less depth according to the throw to be given to the racks, and indicating means controlled by the said racks and indicating the number of pieces of money of 15 different denominations aggregating in amount the total money value of the actuated selective keys.
3. A calculating machine for use in making up pay rolls, comprising selective keys 20 representing money values, a plate carried by each key and provided with vertically arranged spaced notches, denomination translating means comprising vertically movable racks adapted to be engaged and 25 controlled by the said plate on pressing the keys, the notches of each plate being of more or less depth according to the throw to be given to the racks, and counters controlled by the said racks and indicating the number 30 of pieces of money of different denominations aggregating the money value of the keys pressed.
4. A calculating machine, comprising vertically movable selective keys representing 35 money values, notched plates carried by said keys and movable vertically therewith, a series of racks arranged below the notched plates and adapted to be engaged by the
- notches in said plates, the racks being controlled by the said plates, a movable support for each rack, and pivotally connected with the end portions thereof, springs pressing on said supports to hold the racks in uppermost position, and indicating means controlled by the said racks. 45
5. A calculating machine comprising selective keys representing money values and provided with vertically notched plates, denomination racks extending horizontally below the notched plates and mounted to move 50 up and down, the notches of said plates being in register with said racks and of more or less depth according to the throw to be given to the corresponding rack, a movable support for each of the said racks, means for normally holding the supports and the racks in upper-most position, a series of counters, each having a series of number wheels, a pawl and ratchet mechanism for operating the number wheels of each counter, and a segmental gear wheel mounted to swing and in mesh with the said rack, the said segmental gear wheel carrying the pawl of the said pawl and ratchet mechanism. 55
6. In a calculating machine selective keys representing money values, a member carried by each key and having spaced parallel notches, vertically movable racks in register with the said notches and adapted to be engaged by said members, the said notches being of different depths whereby the racks are actuated differentially on pressing the keys, and indicating means controlled by the said racks. 60

In testimony whereof I have signed my name to this specification in the presence of two subscribing witnesses.
